United States Patent Office

Des. 222,790

Patented Dec. 28, 1971

222,790

COMBINED TRAFFIC LIGHT AND STREET SIGN

Lyle E. Gant, Indianapolis, Ind., assignor of a fractional part interest to John W. Guterman, Indianapolis, Ind.

Filed Apr. 2, 1970, Ser. No. 22,206

Term of patent 14 years

Int. Cl. D29—02

U.S. Cl. D72—1

Fig. 1.

Fig. 2.

Fig. 3.

Fig. 4.

Fig.5.

Fig.6.

FIG. 1 is a front elevation of the combined traffic light and street sign showing my design;

FIG. 2 is a top plan view thereof;

FIG. 3 is a side elevation thereof;

FIG. 4 is a rear elevation thereof;

FIG. 5 is an elevation of the side opposite that shown in FIG. 3; and

FIG. 6 is a bottom plan view thereof.

The indicia is shown in broken lines in FIG. 1 for illustrative purposes only.

I claim:

The ornamental design for a combined traffic light and street sign, as shown and described.
